MOP HANDLE ATTACHMENT

Filed March 10, 1927

INTERIOR

Matthew J. Welling

Charles Mills Att.

UNITED STATES PATENT OFFICE

MATTHEW J. WELLING, OF CHICAGO, ILLINOIS, ASSIGNOR TO O-CEDAR CORP'N, A CORPORATION OF ILLINOIS

MOP-HANDLE ATTACHMENT

Application filed March 10, 1927. Serial No. 174,308.

This invention relates to a mop handle attachment and has for its object to provide an attachment which may be readily secured to a mop handle and from which the mop handle may be detached by pivotal movement with respect to the attachment.

It is a further object of this invention to provide a mop handle attachment adapted to be pivotally connected to a mop handle and provided with means for locking said mop handle during a greater part of its range of pivotal movement.

Other and further important objects of this invention will be apparent from the disclosures in the specification and the accompanying drawings.

This invention (in a preferred form) is illustrated in the drawings and hereinafter more fully described.

On the drawings:

Figure 1 is a top plan view of a device embodying the principles of my invention.

Figure 2 is a side elevational view of the same.

Figure 3 is a sectional view taken on line III—III of Figure 1 with parts in elevation.

Figure 4 is a sectional view taken on line IV—IV of Figure 1.

As shown on the drawings:

The reference numeral 1 indicates a triangular shaped plate formed of sheet metal provided with upwardly turned flanged edges 2. Said plate 1, it will be understood, is adapted more especially to be secured to a mop swatch, but may obviously be of any suitable form for use in connection with other devices of similar character, such as scrubbing and polishing devices. The bottom of said plate 1 is stamped upwardly to

provide a raised portion 3 having parallel raised edges 4 and 5. An intermediate groove 6 is formed in said raised portion 3 parallel to said edges 4 and 5. A strap 7 is adapted to be secured to said raised portion 3 by means

of prongs 8 extending through slots in the raised edges 4 and 5 and turned up against the bottom of said raised portion 3. Said strap 7 is provided with a transverse hollow ridge 9 registering with the groove 6 to form a substantially cylindrical opening 10. Said

strap 7 is further provided with an arcuate shaped tongue 11 struck up from said strap, the free end of said tongue being spaced from said strap for a purpose that will later appear.

A member 12 is adapted to be pivotally mounted to said plate 1 and for this purpose is provided with a slot 13 through which the strap 7 may be inserted before being secured to the plate 1. In assembled position said member 12 is pivotally mounted upon the strap 7 with its bottom portion 14 extending through the opening 10 formed by the hollow ridge 9 and groove 6. Said portion 14 is adapted to frictionally engage the walls of said opening 10 so that when the member 12 is swiveled about the portion 14 as an axis, it will remain in any position to which it is moved. Said member 12 is further provided with a transverse slot 15 adapted to receive the tongue 11. A ferrule 16, such as is commonly used on the ends of mop handles, is formed with a lower flattened end 17 adapted to receive the member 12. Said flattened end 17 is provided with a transverse slot 18 adapted to register with the slot 15 in the member 12. The tongue 11 is thus adapted to pass through the coinciding slots 15 and 18 to lockingly secure the ferrule 16 to the plate 1.

It will be understood that a handle may be permanently or semi-permanently secured in the socket of the ferrule 16. The handle and ferrule may then be attached to the attachment 1 by sliding the flattened end 17 of the ferrule over the member 12 while the member 12 is in inclined position, shown in dotted lines in Figure 4. In this position the member 12 is out of engagement with the arcuate shaped tongue 11, so that the ferrule 16 may be slipped over the member 12 until the slots 15 and 18 coincide. The handle and ferrule 16 may then be swung into upright position, the tongue 11 passing through the coinciding slots. Since the tongue 11 will be in engagement with the ferrule 16 and member 12 except for a small portion of the pivotal range of said member 12, there is little danger of the ferrule becoming detached during use of the mop.

It will be appreciated that the attachment

device above described provides quick and simple means for attaching or detaching a handle to a mop head or other similar device. When in attached position the member 12 due to its frictional engagement with the ferrule 16 and with the strap 7 serves as a guide for the mop handle to substantially support the handle in any position.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A mop handle attachment, comprising a ferrule having a flattened end provided with a transverse slot, a mop plate, a slotted member pivoted to said plate and adapted to be inserted into the flattened end of said ferrule and an arcuate tongue secured to said plate and adapted to pass through both of said slots to secure said ferrule to said plate.

2. A mop handle attachment, comprising a ferrule for the end of the mop handle, said ferrule being flattened and provided with a transverse slot in said flattened portion, a plate for attachment to the mop having an upwardly stamped portion provided with spaced slots along opposite raised edges, and an intermediate transverse groove, a strap having prongs secured through the slots in said raised edges and having a transverse hollow rib registering with said transverse groove, a slotted member pivotally mounted upon said strap between said rib and groove, said slotted member being adapted to be inserted into the flattened end of said ferrule so that the slots in said ferrule and in said member coincide, and an arcuate shaped tongue struck up from said strap and adapted to extend through the slots in said slotted ferrule and said member for the greater part of the pivotal movement of said member.

3. A mop handle attachment comprising a ferrule having an apertured end, a member to which a mop may be secured, apertured means pivotally mounted on said member and adapted to be inserted into said ferrule with said apertures coinciding, and means secured to said member adapted to extend through said coinciding apertures only during a part of the distance through which said pivotally mounted means may be moved.

4. A mop handle attachment, comprising a ferrule having an apertured end, a member to which a mop may be secured, apertured means pivotally mounted on said member and adapted to be inserted into said ferrule with said apertures coinciding, and an arcuate tongue struck up from said member adapted to extend through said coinciding apertures during a part of the distance through which said pivotally mounted means may be moved.

5. A mop handle attachment, comprising a ferrule having an apertured end for receiving a handle, a pivotal member slidably connected to said ferrule, a base member arranged to receive a mop, and a strap disposed on said base member for securing said pivotal member thereto, said strap having an arcuate-shaped tongue for engaging said ferrule and said pivotal member for locking said ferrule to said pivotal member and normally permitting pivotal movement of both relative to said base member.

In testimony whereof I have hereunto subscribed my name.

MATTHEW J. WELLING.
